G. H. RIVES.
COMBINED ACCELERATOR PAD AND HEEL REST.
FILED OCT. 21, 1919.

George W. Rives, Inventor
By his Attorney

W. T. Criswell.

Patented Jan. 9, 1923.

UNITED STATES PATENT OFFICE.

GEORGE H. RIVES, OF NEW YORK, N. Y.

COMBINED ACCELERATOR PAD AND HEEL REST.

Application filed October 21, 1919. Serial No. 332,195.

To all whom it may concern:

Be it known that I, GEORGE H. RIVES, a citizen of the United States, and a resident of New York, in the county of New York and State of New York, have invented a certain new and useful Improvement in a Combined Accelerator Pad and Heel Rest, of which the following is a full, clear, and exact specification.

10 This invention relates more particularly to a class of devices adapted to be used in conjunction with automobiles.

My invention has for its object primarily to provide a combined accelerator pad and heel rest designed to be utilized on vehicles, such as automobiles, trucks and the like so that the chauffeur of the vehicle may operate the accelerator pedal with the foot without requiring its contact with the pedal 20 direct, in order to enable positive operation of the pedal at all times since the general formations of pedals of this class are such that the foot of the chauffeur often slips therefrom, and the accelerator pedal, furthermore, frequently becomes highly heated, 25 the device also serving to effectually prevent the shoe of the chauffeur from wearing by avoiding frictional contact of the shoe with the pedal. These advantages are 30 attained mainly by providing a protective cushion element which is movably supported on the vehicle in normal engagement with the accelerator pedal to allow the foot of the chauffeur to be positioned thereon 35 for operating the pedal by moving the cushion as occasion requires.

Other objects of the invention are to provide a rest so that the heel of the shoes of the chauffeur may be comfortably supported 40 when the fore part of the foot is positioned on the protective cushion; to associate with the cushion and the heel rest means for permitting the cushion to be extensibly adjusted relative to the rest; to provide means 45 whereby the heel rest may be hinged to the vehicle; and to provide an accelerator pad and heel rest of a simple, efficient and durable type adapted to be made in any desired size and shape.

50 With these and other objects in view, the invention will be hereinafter more fully described with reference to the accompanying drawing forming a part of this specification in which similar characters of reference 55 indicate corresponding parts in all the

views, and will then be pointed out in the claim at the end of the description.

In the drawing, Figure 1 is a fragmentary sectional view, partly in detail showing a portion of a vehicle with one form of my 60 improved accelerator pad and heel rest applied thereto for enabling the accelerator pedal to be operated.

Fig. 2 is an enlarged top plan of the device.

Fig. 3 is a detail sectional view taken on the line 3—3 of Fig. 2, and

Fig. 4 is a detail sectional view taken on the line 4—4 of Fig. 3.

The device has a heel rest 10 which may 70 be of any suitable shape and size, though this rest preferably consists of a substantially semi-circular flat plate 11 with a flange 12 protruding upwardly from its curved edge and extending from the central part of the straight edge of the plate 75 is an arm or lug or shank as 13. The plate 11 is of a size to freely accommodate the heel of the shoe of the chauffeur or person operating the vehicle, and the flange 12 80 serves to prevent tendency of the heel to slip on the rest 10. Protruding downwardly from the side edges of the arm 13 may be two spaced flanges 14 and 15 to provide a groove 16 extending lengthwise of this arm 85 of the rest. On the underside of the plate 11 centrally of its flanged edge is bolted or otherwise secured, at 17, one leaf, as 18, of a hinge 19 which may be of a commonly known form, and the second leaf 20 of the 90 hinge extends somewhat beyond the heel rest 10. The second leaf 20 of the hinge 19 is in practice screwed, as at 21, to the floor 95 22 of the body, as 23, of an automobile, truck or other vehicle so that the heel rest 10 is suitably spaced from the accelerator pedal, as 24, of the vehicle and so that the free end of the arm 13 of the rest is also spaced from the accelerator pedal.

Normally in contact with the accelerator 100 pedal 24 is a protective cushion element 25 upon which the fore part of the shoe of the foot of the chauffeur rests for operating the pedal as occasion requires. This cushion 105 may be of any desired shape or size, though the one illustrated is approximately oval or elliptic in shape, and the cushion is preferably composed of a plate 26 with a pad 27 made of rubber or other resilient material. The pad 27 is removably held to the 110

plate 26 by one or more metal clips, as 28, 29 and 30, which are provided on the pad so that their ends extend beyond the edge of the pad, and following the arranging of the pad on the plate 26 the clips are bent over the edge of the plate into engagement with its underside.

The protective cushion 25 is movably connected to the heel rest 10 so that the cushion 10 may be extensibly adjusted relative to the rest whereby shoes of various sizes may be accommodated on the device, and serving as means to accomplish this, extending from the plate 26 is a bar 31 which is in the form 15 of a flat plate having downwardly depending spaced flanges 32 and 33. The bar 31 with its flanges are disposed in the groove 16 between the flanges 14 and 15 of the arm 13 of the heel rest 10, and this bar is 20 of a width so that it is freely movable in the groove. Through the central part of the bar 31 in proximity to its free end is a slot 34 extending lengthwise of the bar, and protruding through this slot from the underside 25 of the arm 13 of the heel rest is a threaded pin or bolt 35. The free end of the bolt protrudes below the bar 31, and on the free end of the bolt is a thumb nut, as 36, adapted to be screwed into engagement with 30 the bar for releasably locking the bar 31 with the cushion 25 and the heel rest together. When it is desired to extensibly adjust the cushion 25 relative to the heel rest 10 the nut 36 is loosened on the bolt 35 and 35 the bar 31 with the cushion 25 are slidably moved back and forth with respect to the heel rest according to the adjustment of the cushion 25 as may be desired for properly accommodating the foot of the operator of 40 the vehicle with the heel positioned on the rest 10 and the fore part of the foot arranged on the resilient pad so that by moving the foot accordingly the accelerator pedal will be operated, as occasion requires. Thus a 45 simple, efficient and durable device is provided whereby the chauffeur of an automobile, truck and like vehicle may operate the accelerator pedal without tendency of the foot slipping as well as avoiding damage 50 to the shoes of the chauffeur from wear as well as from the heat when the accelerator pedal becomes heated.

In the foregoing description, I have embodied the preferred form of my invention,

but I do not wish to be understood as limiting myself thereto, as I am aware that modifications may be made therein without departing from the principle or sacrificing any of the advantages of this invention, therefore I reserve to myself the right to 55 make such changes as fairly fall within the scope thereof.

Having thus described my invention, I claim as new and desire to secure by Letters Patent:—

In a combined foot rest and accelerator pedal, a heel portion having an upwardly extending flange on the rear part thereof and downwardly extending flanges on the forward part thereof, the upwardly extending flange extending substantially throughout the path of a semi-circle so as to form a socket for the heel of a shoe, the forward portions of the downwardly extending flanges being parallel so as to form a guideway, a two part hinge having one part riveted to one side of the rear end of the heel portion, the other part of said hinge being adapted to be secured to the foot board of an automobile, a toe portion adjustably connected to the heel portion, said toe portion having downwardly extending flanges on the rear part thereof adapted to slide within and to fit closely adjacent to the downwardly extending flanges on the heel portion, a toe pad of resilient material mounted above the forward end of said toe portion, upwardly extending flanges on the forward end of said toe portion having their upper ends bent down upon said toe pad to hold it in place upon the toe portion, a strip of metal embedded in the rear part of the toe pad having its ends passing through holes in said toe portion, said toe portion having a centrally and longitudinally extending slot on the rear end thereof between the downwardly extending flanges, a bolt extending through the forward end of said heel portion, and a thumb screw on said bolt below the rear end of said toe portion for holding the toe portion in any adjusted position relative to the heel portion.

This specification signed and witnessed this 20th day of October, A. D. 1919.

GEORGE H. RIVES.
